REFRIGERATION

William H. Kitto, Canton, Ohio, assignor to The
Hoover Company, North Canton, Ohio, a cor-
poration of Ohio

Application June 20, 1938, Serial No. 214,657

9 Claims. (Cl. 62—108.5)

This invention relates to refrigeration and more particularly to means for removing ice cubes from a domestic refrigerator tray. In the past it has been necessary to melt the cubes loose from the tray by the application of heat or to remove them by complicated leverage mechanism requiring the removal of the entire grid assembly so that it was necessary to remove all the cubes from a tray at the same time. If only a few cubes were needed, this necessitated the storing of the remainder of the cubes or their wastage. In addition to this the melting of the cubes from the tray by the application of heat, resulted in a further wastage of ice. In using the prior art mechanical leverage devices, it was necessary to anchor or hold the tray down while the cubes were being released. The prior art mechanical devices designed to remove ice cubes from the tray are also cumbersome and complicated in operation and costly to manufacture.

Accordingly, it is an object of this invention to provide an ice tray and grid assembly in which the ice cubes may be released with a minimum of effort and which is simple and easy to manufacture.

Another object of this invention is to provide an ice tray and grid assembly in which it is not necessary to remove the grid assembly from the tray to remove the cubes from the tray and grid assembly.

Another object of the invention is to provide an ice tray and grid assembly in which one, two or more ice cubes may be removed from the tray as desired.

Another object of the invention is to provide an ice tray and grid assembly in which one ice cube may be removed singly or in which two may be removed simultaneously.

Another object of the invention is to provide an ice tray and grid assembly in which it is not necessary to anchor or hold the tray while removing the ice cube from the tray and grid assembly.

Another object of the invention is to provide an ice tray and grid assembly for, and method of, separating the ice cubes from their compartments in which the applied force has no component tending to move the tray along or from the surface upon which it rests or to remove the grid assembly from the tray.

Another object of the invention is to provide an ice tray and grid assembly in which one wall of the cube compartment is moved to induce a force on the cube tending to release the bond be-

tween it and the other walls of the cube compartment.

Another object of the invention is to provide an ice tray and grid assembly for, and method of, releasing ice cubes in which a tension stress is applied to separate the bond between the cube and one wall of the compartment and a shear stress is applied to separate the bond between the cubes and the other walls of the compartment in releasing the ice cube from its compartment.

Another object of the invention is to provide an ice tray and grid assembly in which an ice cube may be raised in a generally vertical direction so that it is accessible for easy removal.

Another object of the invention is to provide a grid assembly for an ice tray, capable of being applied to a standard ice tray.

Another object of the invention is to provide an ice tray and grid assembly in which the grid assembly has a deformable member to release ice cubes individually or in groups.

Another object of the invention is to provide an ice tray and grid assembly having a manually operable lever with a foot extending into the cube compartment to raise the cube from the tray and grid assembly.

Another object of the invention is to provide a tray and grid assembly in which the cube compartments have substantially parallel walls some of which are inclined upwardly and outwardly to facilitate removal of the ice cubes.

Another object of the invention is to provide a grid assembly for an ice tray having a hollow deformable central partition enclosing an air space with means providing for the ingress and egress of the air from the enclosed space.

Another object of the invention is to provide a grid assembly for an ice tray made of flexible non-metallic material, having cube release mechanism molded therein.

Another object of the invention is to provide a grid assembly for ice tray having a central partition member of deformable non-metallic material with metallic cross partition plates molded therein.

Another object of the invention is to provide a grid assembly for ice tray with a hollow deformable central partition member of non-metallic material with deformable ends bonded thereto.

Another object of the invention is to provide a grid assembly for an ice tray having a V shaped central partition member of deformable mate-

rial with a deformable cover member secured to the mouth of the V.

Other objects and advantages of the invention will become apparent as the description proceeds when taken in connection with the accompanying drawing in which:

Figure 1 is a perspective view of an embodiment of the invention;

Figure 2 is a cross sectional view of the device shown in Figure 1;

Figure 3 is a cross sectional view of the device shown in Figure 1 showing a pair of cubes in partially released position;

Figure 4 is a cross sectional view of another embodiment of the invention;

Figure 5 shows a diagram of forces present when a pair of cubes are being released.

The invention herein disclosed comprises a sheet metal tray generally indicated at 10 adapted to be inserted in the freezing compartment of a domestic refrigerator. It is provided with a bottom 11, front and rear walls 12 and 13, respectively, and side walls 14. The side walls 14 are inclined upwardly and outwardly as shown in Figure 2 and the upper edges of the front, rear and side walls are bent outwardly and downwardly to form a rib as shown at 15. The rib 15 is extended outwardly farther above the front wall 12 to form a handle 16.

Removably disposed in tray 10 is a grid assembly generally indicated at 17, which comprises a central partition member 18 and laterally extending partition members 19, 20, 21, 22 and 23 on each side of the central partition member 18. The central partition member 18 is made of flexible material such as rubber and is made hollow so that its side walls 24 and 25 can be easily pressed towards each other. An aperture 26 is provided in the end walls 27 of the central partition member 18 so as to provide for the ingress and egress of air from the cavity so that it will not be necessary to compress the air when the side walls are pressed together.

The central partition member 18 can be molded in one piece with the exception of the end members 27 which can be cemented thereto after the mold is removed. Another way of making the central partition member 18 is to split the side walls 24 and 25 away from each other at the bottom to remove the core and then cement these edges together again. In Figure 4, a third way of making the central partition member 18 is shown. In this modification, the side walls 24 and 25 are molded in one piece in the shape of a V with grooves 28 extending longitudinally of each side wall 24 and 25 near the top. A top member 29 is inserted in the grooves 28 to completely enclose the inside air space except for the aperture 26. The top member 29 may, if necessary, be cemented in the groove 28.

The rubber of the central partition may also be made in a flat sheet, curved to the position shown in Figure 2, the lower edges cemented or vulcanized together and the end members cemented in place.

The laterally extending partition plates 19, 20, 21, 22 and 23 may be made of rubber, made integral with the side walls 24 and 25 of the central partition 18, or they may be made of suitable metal molded into the side walls 24 and 25. One way of molding the laterally extending partition members into the side walls of the central partition member is shown in Figure 4. In this modification, the laterally extending partition members on each side of the

longitudinally extending partition member are made in one piece and extend through the air space in the central partition member as shown at 30. A wire rod, 31, may extend between the various laterally extending partition members in order to hold them against movement with respect to each other.

Molded or otherwise secured in the side walls 24 and 25 of the central partition member 18, 10 between the various laterally extending partition members and between the end partition members 19 and 23, and the end of the tray, are levers 32 and 33. Each of these lever members is provided with outwardly extending foot 15 portions 34 extending into the bottom of each ice cube compartment and upwardly and outwardly extending handle portions 35. Each of the side walls 24 and 25 of the longitudinally extending partition member 18, 20 extend upwardly and outwardly in parallelism with the side walls 14 of the tray when in an unflexed position.

In operation, if it is desired to remove a single ice cube from the tray it is only necessary, for example, to press downwardly on the edge 25 of the tray at A as shown in Figure 1 and press inwardly simultaneously on one of the handle portions 35, such as D and the left hand cube only will be removed. If it is desired to remove two cubes, two handle portions 35 such as C and D shown in Figure 1 are pressed toward each other which lifts two cubes from the tray. In this manner, any or all of the cubes can be removed from the tray. Two of the cubes are shown in raised position in Figure 3 with the central partition member 18 pressed together and by a further flexure of the central partition member, these cubes can be raised to such a position as to be easily grasped and removed from the compartment.

It is to be noted in the operation of removing a cube from its compartment, that a side wall, either 24 or 25 on the central partition member is torn from the cube and at the same time the foot portion 34 exerts an upward pressure on the cube. This induces a tearing stress on the bond between the central partition 18 and the cube and a tension stress on the bond between the cube and the bottom of the tray. At the same time the force exerted by the foot, 34, induces a shear stress on the bond between the cube and the remaining three walls of the compartment.

It is also to be noted that all forces exerted in removing two cubes from the tray are balanced 55 against each other so that there is no force tending to move the tray along or from the surface upon which it rests nor to lift the grid assembly from the tray. Figure 5 of the drawing shows a diagrammatic representation of the forces present when two cubes are moved from the tray simultaneously. Suppose force F is applied to each of the handle portions 35 of levers 32 and 33. This will tend to rotate each of the levers about a fulcrum with the result that the resistance of the ice cube to movement represented by the force F^1 will press downwardly, on the end of each foot portion 34. The resultant of the forces F and F^1 can be resolved into vertical and horizontal components represented by forces F^2 and F^3 . The force F^3 on one lever will be balanced by an equal and opposite force F^3 on the other lever and the two forces F^2 will merely exert a downward pressure on the bottom 11 of the ice tray. It can thus be seen that the only force tending to move either the tray or

the grid assembly from the tray is a downward pressure on the bottom of the tray. This renders it unnecessary to hold or anchor the tray against movement when releasing two cubes simultaneously. It is also to be noted that no force is required to hold the grid assembly in the tray.

From the above it can be seen that any or all the cubes can be easily removed from the tray without the necessity of removing the grid assembly from the tray. This is of particular advantage when only one or two cubes are needed since the remainder remain in their original frozen condition and can be kept for future use. The grid assembly need not be made removable but can be secured to the tray in any desired manner. The preferred form, however, is to make the grid assembly removable so that the tray and grid assembly can be readily cleaned, and the grid assembly can be applied to standard trays.

The hollow central partition member renders it easy to press levers 32 and 33 toward each other to release the cubes and the fact that the air space is entirely enclosed, except for the aperture 26, renders it certain that no water can get into the air space and prevent operation of the levers.

It can be seen from the foregoing description that this invention provides a simple and easy way to manufacture ice tray and grid assemblies in which ice cubes can be removed easily and with a minimum of effort and bother.

While I have illustrated and described only one embodiment of my invention, it is to be understood that this embodiment is to be taken as illustrative only and not in a limiting sense. I do not wish to be limited to the exact disclosure but to include all equivalent variations except as limited by the scope of the appended claims.

I claim:

1. In combination, an ice tray, a grid assembly positioned therein to form ice cube compartments, said grid assembly comprising, a longitudinally extending partition of deformable material and means on said deformable partition for lifting cubes from their compartments, individually or in groups.
2. In combination, an ice tray, a grid assembly positioned therein to form ice cube compartments

50

and including a longitudinal partition and lever means forming an integral part of said partition and mounted thereon and extending into said cube compartments, said lever means being so mounted as to raise ice cubes from their compartments when pressure is applied thereto.

3. An ice cube tray and grid assembly having a hollow covered deformable central partition enclosing an air space with means providing an inlet and outlet for air.

4. An ice cube tray grid assembly having a central partition of deformable material with levers positioned along said partition for raising ice cubes.

5. An ice cube tray grid assembly comprising, a central partition of deformable non-metallic material and metallic cross partition members molded therein.

6. An ice cube tray grid assembly comprising a hollow central partition of deformable material and end closures of deformable material bonded thereto.

7. An ice cube tray grid assembly comprising a hollow central partition of deformable material, said partition comprising a portion V shaped in section and a cover member secured thereto.

8. In combination, an ice tray, a grid assembly positioned therein to form ice compartments, and a leverage system forming a permanent part of said grid assembly for breaking the bond between the ice and compartment walls, said leverage system being so constructed and arranged that oppositely acting forces may be applied thereto during the breaking of the bond and all reactive forces acting upon said tray other than in a downward direction are balanced within the grid assembly itself.

9. In combination, an ice tray, a grid assembly positioned therein to form ice compartments, and a pair of levers mounted on said grid assembly for breaking the bond between the ice and compartment walls, said levers being so constructed and arranged that oppositely acting forces may be applied thereto during the breaking of the bond, which result in reactive forces being impressed on said tray by one lever which are balanced by the reactive forces impressed by the other lever except those reactive forces tending to move the tray in a downward direction.

WILLIAM H. KITTO.
